DEFROST CONTROL FOR REFRIGERATION SYSTEMS

Carl A. Smith, Ferguson, Mo., assignor to Missouri Automatic Control Corporation, St. Louis, Mo., a corporation of Missouri

Application April 6, 1950, Serial No. 154,230

7 Claims. (Cl. 161—1)

1

This invention relates generally to control devices for refrigeration systems which employ a compressor for compressing a gaseous refrigerant, a condenser for cooling and liquefying the refrigerant and an evaporator coil wherein the refrigerant vaporizes and expands to cool the coil and the surrounding area to be refrigerated and is thereafter periodically returned to the compressor to again be compressed. It more particularly concerns an automatic defrost control device adapted to be used in a system as above for periodically interrupting operation of the compressor for an interval sufficient to permit the temperature of the evaporator coil to rise to a point wherein any frost accumulations thereon will be melted and in which this interval is terminated in response to a predetermined increase in the refrigerant pressure in the return conduit from the evaporator to the compressor.

The normal operation of the compressor in such systems is usually intermittent and is ordinarily controlled by a normal operation control device which may be responsive to either the temperature of the space to be refrigerated, the temperature of the evaporator coil or the pressure of the refrigerant in the return line to control operation of the compressor so as to maintain a preselected temperature of the refrigerated space. The automatic defrost control device in the present invention is arranged to override such normal operation control devices and to interrupt compressor operation at preselected intervals for a period sufficient to insure defrosting of the evaporator and is responsive to restore control of the compressor to the normal control device only at a pressure which is substantially higher than the high pressure or corresponding high temperature to which the normal control device responds to start operation of the compressor.

It is an object of the present invention to provide a generally new and improved fully automatic defrost control device of the above character which is capable of initiating defrost periods at preselected intervals and is operative to terminate the defrost periods in response to a predetermined fluid pressure.

A further object is to provide an automatically operated, heavy duty, double break switching device having a snap action in both directions suitable for the control of a refrigeration compressor circuit in which the switch is caused to be actuated to a circuit breaking position at a preselected time by a chronometric device and in which the switch is subsequently caused to

2

be actuated to a circuit closing position in response to a predetermined increase in the pressure of the refrigerant in the return line between the evaporator and the compressor.

- 5   A further object is the provision of a refrigeration defrost control having switch structure which is normally biased in one operative position by resilient means and in which the energy of a low torque synchronous timing motor is accumulated over a period of time to be released at a predetermined time to oppose said resilient means and cause actuation of the switch to an opposite position with a snap action and wherein said resilient means is restrained by latch means 10 and is subsequently released in response to a predetermined fluid pressure to cause the switch structure to be again operated to the first position with a snap action by the resilient means.

15   Further objects and advantages will become apparent upon reading the following description and accompanying drawings.

In the drawings:

Fig. 1 is a diagrammatical illustration of a refrigeration system in which is incorporated a 20 defrost control device constructed in accordance with the present invention;

Fig. 2 is a front elevation of the defrost control device shown in Fig. 1;

Fig. 3 is a side elevation of the defrost control device shown in Fig. 1;

30   Fig. 4 is an enlarged left side elevation of the control shown in Fig. 2 with its casing shown in cross section;

Fig. 5 is a right side elevation of the control shown in Fig. 2 with its casing removed;

35   Fig. 6 is an elevation of the control shown in Fig. 2 with its casing removed;

Fig. 7 is a top view of the control shown in Fig. 2 with its casing removed;

Fig. 8 is a rear elevation of the control shown 40 in Fig. 2 also with its casing removed;

Figs. 9 to 12 inclusive are different operative views of the switch actuating mechanism and are taken generally on line 9—9 of Fig. 4;

45   Fig. 13 is a slightly enlarged sectional view showing the main shaft and cam arrangement and is taken on line 13—13 of Fig. 6;

Fig. 14 is a perspective view of the pressure actuated trip lever;

50   Fig. 15 is a perspective view of the cam actuated trip lever;

Fig. 16 is a perspective view of the switch actuating lever; and

Fig. 17 is a perspective view of the spring load- 55 ing lever.

The refrigeration system diagrammatically illustrated in Fig. 1 includes as primary elements a compressor 10, an electric compressor driving motor 11, a condenser 12, a receiver 13 and an evaporator coil 14. The output side of the compressor 10 is connected to one end of the condenser by conduit 15 and the other end of the condenser is connected to one end of the receiver 13. The other end of the receiver is connected to the evaporator coil 14 by a conduit 16. Interposed in the conduit 16 is a conventional thermostatically controlled expansion valve 17 having a temperature sensitive bulb 18 located so as to be sensitive to the temperature of the evaporator 14. The lower end of the evaporator coil is connected to the intake of the compressor by a conduit 19.

The electric driving motor 11 is provided with an energizing circuit comprising the leads 20 and 21 which are connected to a suitable source of electrical power. Interposed in the leads 20 and 21 is a conventional normal operation control device generally indicated at 22 which functions to control the normal operation of the compressor in accordance with cooling requirements and may be a pressure actuated switch as shown in the illustration which is responsive to the pressure of the refrigerant in the return line 19 between the evaporator and the compressor. The control 22 is also indicated as being a double break switching device in which both sides of the circuit are broken.

Also interposed in the compressor motor circuit and in series with the normal control device 22 is a defrost control device generally indicated at 23 which is constructed in accordance with the present invention. A manually operated master switch is also provided for control of the compressor motor circuit and is indicated at 24. The defrost control device 23 includes a frame comprising a rear panel member 25 and a front panel member 26 which are spaced and securely connected at several points as by spacers 27 and screws 27a. At their lower right hand corners the panel members 25 and 26 have integral portions 28 and 29 formed horizontally at right angles therewith and have attached thereto as by screws 30 the flange of a cup element 31. Mounted on the upper right hand corner and on the front side of rear panel 25 in Fig. 6 is an electrically operated synchronous timer motor generally indicated at 32. The motor has a casing 33 provided with perforated ears 34 through which pass screws 35 for attachment of the motor to the rear panel member 25. The timer motor may be of conventional commercial type which includes speed reduction gearing contained within the casing 33 and has a power take off shaft 36 projecting rearwardly through the rear panel 25 to which is keyed a small pinion gear 37. The timer motor may also be provided with the usual ratchet clutch which permits advancing the power take off shaft without rotating its internal reduction gear train.

There is a horizontal rotatable shaft 38 supported in the front and rear panel members 25 and 26. One end of shaft 38 extends rearwardly of the rear panel 25 and has fixed thereto a spur gear 39. Between the pinion gear 37 and the spur gear 39 is an intermediate gear 40 mounted for rotation on a shaft 41 which is supported in the rear panel 25. The gears 37, 39 and 40 are in mesh as indicated in Fig. 8 and the shaft 38 is thereby driven by the synchronous motor 32. The intermediate gear 40 serves to further reduce

the speed of the shaft 38 as is apparent. The shaft 38 also extends forwardly of the front panel 26 and has rigidly attached to its end as by a set screw 42, a knurled hub member 43. Rigidly attached to the inner end of the hub member 43 as by riveting at 44 is a disc like dial 45 having the periphery on its front side divided into 24 equal divisions representing hours. Surrounding the shaft 38 and extending between the hub member 43 and the rear panel 25 is an inner sleeve member 46 which carries rigidly attached to its rearward end as by riveting a first trip cam 47. Surrounding the inner sleeve 46 is an outer sleeve 48 which carries rigidly attached thereto at its rearward end a second trip cam 49. Also carried on sleeve 48 and rigidly attached thereto by means of a set screw 50 passing through its integral hub is a double lobed loading cam 51.

At their forward ends the sleeve members 46 and 48 carry hub members 52 and 53 respectively rigidly attached thereto as by set screws 54 and 55. The hub members 52 and 53 have rigidly attached thereto as by riveting a pair of adjusting arms 56 and 57 respectively. The outer ends of the adjusting arms are formed over as at 58 and 59 and receive the periphery of the dial 45. There are screws 60 and 61 which pass through these U-formed end portions of the adjusting arms whereby they may be clamped tightly in an adjusted position on the periphery of the dial. The inner and outer sleeves carrying the cams 47 and 49 are therefore driven by the shaft 38 through the dial disc and the adjusting arms. The ends of the adjusting arms which overlay the periphery of the dial are pointed so as to facilitate accurate indexing with indicia on the dial face. The adjusting arm 56 carries at its inner end a stop pin 62 which is engaged by a projection 63 at the inner end of adjustable arm 57 and which limits the relative rotation of the two adjusting arms. By the arrangement described it will be seen that the second tripping cam 49 and the spring loading cam 51 are fixed with relation to each other and that the first tripping cam 47 which is attached to the inner sleeve 46 may be rotated relative to the second tripping cam 49 and the spring loading cam 51 by rotating the adjusting arm 56. The spring loading cam 51 is provided with two lobes 51a and 51b for a purpose to be explained hereinafter.

Mounted on the upper left hand corner and on the front side of rear panel 25 are two pairs of switch blades 64 and 64a and 65 and 65a which carry contacts 64b and 64c and 65b and 65c respectively. The switch blades are carried on an angle bracket 66 and are assembled, together with suitable spacing insulators on screws 67 by which they are attached to the bracket 66. Provision for adjustably positioning the bracket 66 on the panel is made by providing a slot 68 in the rear panel 25 through which passes a screw 69 and is threadedly engaged in the bracket 66 at one end thereof and a screw 70 passing through a clearance hole in the rear panel and threadedly engaging the bracket at its other end. The resilient switch blades are formed so that the contacts which they carry are normally held open.

Pivotedly mounted between the front and rear panels on a pivot 71 which is supported in the panels is a generally L-shaped switch actuating arm 72 which carries at its upper end rigidly attached thereto an abutment element 73 of dielectric material which is adapted to engage the lower switch blades 64a and 65a and to move them upward and to close the contacts as the switch actuating arm 72 is rotated clockwise about its pivot

11. Pivotably adjacent the lower end of arm 72 on a pivot 74 which is supported in the front and rear panel members, is a horizontal cam actuated trip arm 75 having a laterally extending platform portion 76 which under certain conditions is abutted at its edge by the lower end of the switch operating arm 72 whereby the arm 72 is restrained from counterclockwise rotation. The cam actuated trip arm 75 is normally urged in a clockwise direction about its pivot 74 by a spring 71. Arranged generally parallel with the long vertical leg of the switch actuating lever 72 and pivotably at its upper end on a pivot 78 is a spring loading arm 79. The lower free end of the arm 79 lies adjacent the double lobed cam 51 and as the cam is rotated counterclockwise the arm 79 is rotated counterclockwise about its pivot 78. The arm 79 is provided with a lateral portion 80 which is engaged by the lobes of cam 51. The lateral portion 80 of arm 79 has a cut out portion 80a for a purpose to be described later.

The spring loading arm 79 has pivotally attached thereto on a pivot 81, a pin 82 which extends horizontally through an aperture in the switch actuating lever 72 and has a nut 83 on its outer threaded end. The pin 82 is provided with a collar or flange 84 at its inner end and a coil spring 85 is provided which surrounds the pin 82 and bears against the collar 84 at one end and the switch actuating lever 72 at its other. A spring 86 attached at one end to the arm 72 and at its other end to an anchor pin 87 mounted in the panel members, urges the arm 72 in a clockwise switch closing direction. The spring 85 is, however, considerably stronger than the spring 86 and is capable of readily overcoming it. The pressure actuated trip arm 75 carries at its outer end a roller 88 adapted to be engaged by the lobes of cams 47 and 49 which as these cams are rotated counterclockwise cause the trip arm 75 to be rotated counterclockwise, thereby causing the lower end of arm 72 to become disengaged from the horizontal portion 76 of the trip arm.

Mounted in the cup element 31, see Fig. 10, is a collapsible bellows 89 having its upper end firmly attached and sealed to the inner wall of the cup element 31 at 90 and having its lower end movable. The lower end of the cup element 31 is provided with a suitable fitting 91 for the purpose of attaching a conduit 92, see Fig. 1, by which the cup element is connected with the return line from the evaporator coil to the compressor at 93. There is an adjustable bellows stop screw 95 threadedly engaged in the fitting 91 for limiting the downward travel of the lower free end of the bellows. The stop screw 95 has a small longitudinal passage 96 therethrough and a connecting cross passage 96a therethrough to provide communication to the interior of the cup element.

Resting on the inner side of the lower free end of the bellows and extending upwardly therefrom is an actuating pin 97. The pin 97 is guided in a bushing 98 carried by a horizontal plate 99. The plate 99 is clamped between the flange of the cup element and the lower horizontally formed portions 28 and 29 of the rear and front panel members. Mounted above the bellows 89 on a pivot 100 is a horizontally arranged pressure actuated trip lever 101. The upper end of actuating pin 97 engages the under side of lever 101 immediately to the right of its pivot 100 and causes its counterclockwise rotation when a predetermined pressure increase is communicated to the lower part of cup element 31 causing the bellows 89 to be contracted and the actuating pin 97 to be

moved upward. At its right end the pressure actuated trip arm 101 is engaged on its upper side by an adjustable pressure opposing spring 102. Tension of spring 102 is made adjustable by the provision of an internally threaded sleeve 103 bearing against the upper end of the spring and by an engaging threaded adjusting screw 104 which is rotatably mounted in a bracket 105 attached to the rear panel 25 as by screws 106.

10 The left hand end of pressure actuated trip lever 101 is forked as at 101a and receives the stem of a vertically acting latch member 107. Latch member 107 is guided vertically as by slots 108 in the latch which receive horizontal guide pins 109 supported in a bracket 110. The latch 107 is normally urged upward by a spring 111 which bears against a flange 112 on the stem thereof. The upper end of latch 107 is adapted to engage the lower free end of the spring loading arm 79, as indicated. The upper end of the latch member 107 is beveled as at 113 so that as the arm 79 is rotated counterclockwise by the cam 51 it may depress the latch and be permitted to move into a latched position.

25 25 There is a rectangular cut out in the left hand side of rear panel 25 in which is mounted as by rivets 114, a terminal panel 115 of dielectric material, see Figs. 6 and 8. Mounted in panel 115 are terminal posts 116 to which external main leads 20 and 21 are connected on the front side of the panel and to which internal wiring leads 20a, 20b and 21a, 21b are connected on the rear side. The internal leads 20a, 20b, 21a and 21b are connected at their other ends to the switch blades 64, 64a, 65 and 65a respectively. A parallel circuit for continuous energization of the synchronous timer motor 32 is provided by the internal leads 20c and 21c which connect the motor across the main leads 20 and 21 as shown in Fig. 8. There is also a resistor 116a interposed in the lead 20c which may be provided to drop the voltage so as to accommodate commercially available synchronous motors.

30 40 45 The defrost control device 23 is provided with a rectangular open front casing 117 having a back and four sides and a front cover member 118 having two rearwardly formed sides which overlay opposite sides of the casing and is removably attached thereto by the provision of open end slots 119 and screws 120, see Figs. 2, 3 and 4. The control mechanism is removably mounted in the casing as by attachment of the rear panel 25 to the rear side of the casing by screws 121 and spacing rods 122 which are in turn attached to the casing as by riveting, see Fig. 4. It is also attached to the lower side of the casing as by screws 123 and feet 124 which are formed as part of the plate member 99, see Figs. 10 to 12. The cover member 118 has a round window 125, see Fig. 4, concentric with the dial 45 which is provided with a transparent plastic disc 126 attached to the cover as by rivets 127. The plastic disc has a central aperture through which projects the knurled hub member 43. There is also provided a fixed index pointer 128 which is attached to the front panel member 26 as by a rivet 129 and which has a pointed end which under lies the transparent window.

In operation

When the master switch 24 is closed the timer motor is in operation and causes the shaft 38 to rotate in a counterclockwise direction as indicated by the arrows. The gear reduction from

the timer motor to the shaft 38 may be varied to suit requirements, in the present arrangement the gear reduction is such that the shaft 38 makes one revolution in 24 hours.

Referring to Fig. 9 in the drawings; in this operative view the defrost control is inoperative to affect the compressor motor circuit and operation of the compressor is therefore under control of the normal control device 22. The switch contacts 64b—64c and 65b—65c being closed by reason of the return spring 86. The spring loading arm 79 is resting on a low point of the cam 51 thus permitting the spring 86 to rotate the switch actuating lever 12 clockwise to close the switch contacts. The pressure actuated trip arm is shown rotated, due to pressure acting through the pin 97, to a position in which the latch 107 is moved downward out of engagement with the spring loading arm 79, and the cam actuated trip lever 75 is in its normal horizontal position with its follower roller 88 riding the lower parts of cams 47 and 49. In this position the lower end of switch actuating arm 12 will, of course, engage the horizontal portion 76 of the cam actuating trip lever 75.

In Fig. 10, the rotation of shaft 38 has progressed to a point wherein lobe 51a of the cam 51 has moved the spring loading lever 79 counterclockwise to a point wherein the latch member 107 is now engaging its lower end and wherein the relatively strong spring 85 is compressed. Also in this position the pressure actuated trip lever 101 has been rotated to its normal horizontal position by the spring 102 which is permitted as a consequence of a decrease in pressure in the lower part of cup element 31 acting on the bellows 88. In this position the relatively strong spring 85 is now stressed to a point where it is capable of rotating the switch operating arm 72 counterclockwise in opposition to the spring 86 which will result in opening of the contacts.

In Fig. 11, the rotation of shaft 38 has progressed to a point wherein the high point of the lobe 51a of cam 51 has cleared the edge of the cut out portion 80a of the lateral portion 80 of the spring loading arm 79 and the trip cam 49 has progressed to a point wherein its lobe is starting to engage the roller 88 of the cam actuated trip arm 75. Other elements of the mechanism remain in the same position as indicated in Fig. 10.

In Fig. 12, the rotation of shaft 38 has progressed to a point wherein the lobe of tripping cam 49 has rotated the cam actuated trip arm 15 counterclockwise moving its horizontal portion 76 out of engagement with the lower end of the switch actuating arm 72 thus permitting the rapid counterclockwise rotation of arm 12 under the urging of the relatively strong spring 85. When this occurs the dielectric contacting member 13 attached to the upper end of the switch operating arm 72 leaves the lower switch arms 64a and 65a permitting the switch contacts to part rapidly due to the inherent resiliency of the lower switch blades. The spring loading arm 79, however, is retained in its latch position by the latch 107. In this position the compressor motor energizing circuit is broken and the defrost period is initiated.

During the interval which follows, the pressure in the return line from the evaporator to the compressor, which is communicated to the lower part of cup element 31, will gradually build up due to inoperation of the compressor.

and when it reaches a predetermined high point, the opposing spring 102 will be overcome and the pressure actuated trip lever 101 will be rotated counterclockwise about its pivot 100 thereby forcing the latch 107 downward out of engagement with the lower end of the spring loading arm 78. When this occurs the spring 86 is permitted to again return the switch actuating arm rapidly in a clockwise direction causing the switch contacts to be again closed with a snap action and the elements of the mechanism to return to the positions as shown in Fig. 9. The defrost period is thus terminated and control of the compressor operation is returned to the usual normal control device.

The pressure at which the pressure actuated cam 101 trips the latch 107 may be varied by varying the tension of the opposing spring 102. This is accomplished by rotating the spring adjusting screw 104. By the provision of the two lobes 51a and 51b on the spring loading cam 51 and the provision of the two tripping cams 47 and 49, two defrost periods may be caused to occur at unequal intervals in one revolution of the 24 hour dial. Also by the described arrangement in which the trip cam 47 is angularly adjustable with relation to the trip cam 49, the intervals at which the defrost periods are initiated may be varied.

0 The foregoing description and accompanying drawings are intended to be illustrative and not limiting the scope of the invention being set forth in the appended claims.

[claim:

35 1. In a device of the kind described, a control member, a movable actuating member operatively associated with said control member, a first spring for urging said actuating member in one direction, a first releasable latch means operative to restrain movement of said lever in an opposite direction once it has been moved to a predetermined position by said first spring, a cam follower, a second stronger spring operatively connected at one end to said cam follower and at its other 40 end to said actuating member, a first cam for moving said cam follower in a direction to stress said second spring in opposition to said first spring, and for moving it to a position wherein 45 said second spring is stressed a predetermined amount, a second releasable latch means for holding said cam follower in said position once it has been moved to said position, a second cam for releasing said first latch means, means for driving said cams at a predetermined rate of speed, 50 said cams being arranged to act in the order recited, whereby said second spring is first stressed between said cam follower and said actuating member by said first cam and thereafter, said 55 first latch means is released by said second cam permitting said stressed second spring to move 60 said actuating member oppositely against said first spring, and pressure responsive means for releasing said second latch means, thereby to permit the return of said cam follower and said actuating member by the action of said first spring, 65

2. In a device of the kind described, a control member, a pivoted lever operatively associated with said control member, a first spring for urging said lever in one direction, a cam follower adjacent 70 said lever, a second stronger spring operatively connected at one end to said cam follower and at its other end to said lever and being capable when stressed of overcoming said first spring, a first releasable latch means operative to restrain 75 movement of said lever in an opposite di-

rection once it has been moved to a predetermined position by said first spring, a first cam for moving said cam follower in a direction to stress said second spring in opposition to said first spring and for moving it to a position in which said second spring is stressed a predetermined amount when said latch means is effective to restrain the opposite movement of said lever, a second releasable latch mean operative to restrain said cam follower against its return from said position once it has been moved to said position, a second cam for releasing said first latch means, a shaft for said cams, means for driving said shaft at a predetermined rate of speed, said cams being mounted for rotation with said shaft and being arranged to act in the order recited when said shaft is rotated by said driving means, whereby said second spring is first stressed between said cam follower and said lever by said first cam and whereby thereafter, said first latch means is released by said second cam thereby permitting said stressed second spring to move said lever in an opposite direction against said first spring, and a pressure responsive actuator responsive to a predetermined pressure to release said second latch means, thereby to permit the return of said cam follower and said lever by the action of said first spring.

3. In a device of the kind described, a control member, a movable actuating member operatively associated with said control member, a first spring for urging said actuating member in one direction, a first releasable latch means operative to restrain movement of said actuating member in an opposite direction once it has been moved to a predetermined position by said first spring, a cam following member, a second stronger spring operatively connected at one end to said cam follower and at its other end to said actuating member, a first cam for moving said cam follower in a direction to stress said second spring in opposition to said first spring, and for moving it to a position wherein said second spring is stressed a predetermined amount when said latch means is effective to restrain said actuating member, a second releasable latch means for holding said cam follower in said position once it has been moved to said position, a second cam for releasing said first latch means, a shaft for said cams, means for driving said shaft at a predetermined rate of speed, said cams being mounted for rotation on said shaft, a cam driving member fixed to said shaft for rotation therewith, independent adjusting means for each of said cams, each of said adjusting means having a portion fixed to one of said cams and having a second portion adapted to releasable clamping engagement with said driving member, whereby said cams may be angularly adjusted with respect to said shaft in such manner that said first cam acts first to stress said stronger spring and whereby said second cam may be adjusted with relation to said first cam thereby permitting selection of the interval between the time at which said stronger spring is stressed and the time at which said second cam effects the release of said first latch means, and means responsive to a predetermined pressure for effecting the release of said second latch means.

4. In a device of the kind described, a control member, a movable actuating member operatively associated with said control member, a first spring for urging said actuating member in one direction, a first releasable latch means operative to restrain movement of said actuating member in

an opposite direction once it has been moved to a predetermined position by said first spring, a cam follower, a second stronger spring operatively connected at one end to said cam follower and at its other end to said actuating member, a first cam for moving said cam follower in a direction to stress said second spring in opposition to said first spring, and for moving it to a position wherein said second spring is stressed a predetermined amount when said latch means is effective to restrain said actuating member, a second releasable latch means for holding said cam follower in said position once it has been moved to said position, a second cam for releasing said first latch means, said cams being arranged to act in the order recited, a power operated chronometric device, a member driven by said chronometric device, means for adjustably connecting said cams to said driven member whereby the interval between any instant and the time at which said second cam effects the release of said first latch means may be selected, and means responsive to a predetermined pressure for effecting the release of said second latch means.

5. In a device of the kind described, a control member, a movable actuating member operatively associated with said control member, a first spring for urging said actuating member in one direction, a first releasable latch means operative to restrain movement of said actuating member in an opposite direction once it has been moved to a predetermined position by said first spring, a cam follower, a second stronger spring operatively connected at one end to said cam follower and at its other end to said actuating member, a first cam for moving said cam follower in a direction to stress said second spring in opposition to said first spring, and for moving it to a position wherein said second spring is stressed a predetermined amount when said latch means is effective to restrain said actuating member, a second releasable latch means for holding said cam follower in said position once it has been moved to said position, a second cam for releasing said first latch means, said cams being arranged to act in the order recited, a power operated chronometric device, a member driven by said chronometric device, means for adjustably connecting said cams to said driven member whereby the interval between any instant and the time at which said second cam effects the release of said first latch means may be selected, and means responsive to a predetermined pressure for effecting the release of said second latch means.

6. In a device of the kind described, a control member, a pivoted actuating lever operatively associated with said control member, a first spring for urging said actuating lever in one direction, releasable latch means operative to restrain movement of said lever in an opposite direction once it has been moved to a predetermined position by said first spring, a cam follower, a second stronger spring operatively connected at one end to said cam follower and at its other end to said actuating lever and being capable when stressed of readily overcoming said first spring, a first rotating cam for moving said cam follower in a direction to stress said second spring in opposition to said first spring when said latch means is effective, a second cam for releasing said latch

11

means, and means for driving said cams at a predetermined rate of speed, said cams being arranged to act in the order recited, whereby said second spring is first stressed between said cam follower and said lever by said first cam and whereby thereafter said latch means is released by said second cam permitting said stressed second spring to move said actuating lever in an opposite direction with a snap action against said first weaker spring.

7. In a device of the kind described, a control member, a first spring means for biasing said control member in a first position, a pivoted actuating lever arranged to engage said control member and to move it oppositely to a second position when said lever is moved in one direction, a second stronger spring for moving said lever in said direction, releasable latch means operative to restrain movement of said lever in an opposite direction once it has moved said control member to its second position, a cam follower, a third spring stronger than said second spring operatively connected at one end to said cam follower and at its other end to said actuating lever and being capable of readily overcoming said second

12

spring when stressed, a first rotating cam for moving said cam follower in a direction to stress said third spring in opposition to said first spring when said latch means is effective, a second rotating cam for releasing said latch means, and means for rotating said cams at a predetermined rate of speed, said cams being arranged to act in the order recited, whereby said third spring is first stressed between said cam follower and said lever by said first cam and whereby thereafter said latch means is released by said second cam permitting said stressed third spring to move said actuating lever oppositely with a snap action against said second spring and permitting said control member to be moved in a snap action to its first position by said first spring.
